ROTATOR ATTACHMENT FOR PUMPING JACKS

James O. Wilson, Strawn, Tex.

Application July 24, 1941, Serial No. 403,918

2 Claims. (Cl. 74—21)

This invention relates to an attachment for pumping jacks of deep well pumps and more particularly to an attachment for rotating the polish or well rod on each stroke thereof, thereby keeping the well rod from scoring and for smoothing out old scores and grooves in the rod thus increasing the life of the rod and of gland packings.

Among the particular advantages of the attachment are: That it will prevent well rods and rod joints from wearing flat which occurs especially in crooked holes and where crooked sucker rods are used; that it will turn well rods always in a clockwise direction to prevent the suction rod joints from being unscrewed and uncoupled; and that it will operate on the down stroke of the well rod to prevent the sand cutting grooves in the valve cups and scoring the working barrel and that could be used on inserted pumps for rotating the pump tube.

A particular advantage of the invention resides in the fact that it is constructed and arranged to operate on the down or gravity stroke of the well rod so that no increase of or additional power is required to operate the attachment due to the fact that the pumping jack operates only for raising the well rod.

A further aim of the invention is to provide an attachment of the above described character that is of simple construction and capable of being economically manufactured; and which may be readily applied to well rods and pumping jacks already in use and of conventional construction without affecting their normal operation.

Other objects and advantages of the invention will hereinafter become more fully apparent from the following description of the drawing which illustrates a preferred embodiment of the invention, and wherein:

Figure 1 is a side elevational view showing the rotator attached to a polish or well rod and its pumping jack,

Figure 2 is a top plan view of a part of the rotator,

Figure 3 is a side elevational view of the part shown in Figure 2, and

Figure 4 is a transverse vertical section view taken substantially along the plane of the line 4—4 of Figure 3.

Referring more particularly to the drawing, wherein like reference characters designate like or corresponding parts throughout the different views, 10 designates generally a conventional pumping jack having a rocking frame 11 which is

pivotedly mounted at 12 and which is connected to a walking beam 13 thereof by means of a pitman 14. The free end of the walking beam 13 is connected in a conventional manner to a polish or well rod 15 near the upper end thereof.

Previously described parts are all of conventional construction and are shown and described merely to illustrate the application of the rotator attachment, designated generally as 16, and comprising the invention. The attachment 16 includes a ratchet wheel 17 which is keyed to the well rod 15 above the beam 13 and between a pair of collars 18. A bar 19 is turnably mounted on the rod 15 and is disposed to rest on the upper collar 18, said bar being connected to the rod 15 intermediate of its ends. A second bar 20 is turnably mounted adjacent one end thereof, on the well rod 15 and is disposed below the lower collar 18. The bar 20 is connected intermediate of its ends to one end of the bar 19 by means of an outer nut and bolt fastening 21 and an inner nut and bolt fastening 22. The bars 19 and 20 and the nut and bolt fastenings 21 and 22 combine to form a lever 23 which is turnably mounted on the well rod 15 and supported thereon by the collars 18.

The opposite end of the bar 18 is provided with longitudinally spaced apertures 23 for selectively receiving a nut and bolt fastening 24 to which is connected the counterweight 25 for a purpose which will hereinafter be described.

The free end of the bar 20, which extends beyond the first mentioned end of the bar 19, likewise is provided with a series of longitudinally spaced openings 26 for selectively receiving a nut and bolt fastening 27 to which is swivelly connected an inverted yoke shaped member 28 which depends from the bar 20.

The connecting rod 29 is provided with an eye 30 at one end thereof, which is disposed in the yoke-shaped member 28 and connected thereto by means of pin 31, to thereby provide a universal connection between the connecting rod 29 and the lever 23. The opposite end of the connecting rod 29 is provided with an eye 32 which is pivotally connected in any suitable manner, as at 33, to a portion of the rocking frame 11.

An elongated, longitudinally disposed ratchet dog 34 is pivotally connected at one end thereof to the nut bolt fastening 21, between bars 19 and 20. The dog 34 extends outwardly from the side of the lever 23, opposite to the side from which the connecting rod 29 projects, and toward the ratchet wheel 17, and the free end thereof is curved inwardly and toward said ratchet wheel

and is adapted to engage between teeth thereof, as best seen in Figure 2. A staple or eye 35 is secured in the ratchet dog 34, intermediate of the ends thereof, and projects from the inner side thereof. A contractile coil spring 36 is connected at one end thereof to the staple 35 and has its opposite end anchored to the fastening 22 for urging the ratchet dog 34 to swing inwardly toward the lever 23.

From the foregoing will be obvious that when the lever 23 is turned in a clockwise direction, as seen in Figure 2, the free end of the dog 34 will be held engaged with teeth of the ratchet wheel 17, by the spring 36, causing the ratchet wheel 17 and the rod 15 to turn with the lever 23. On the other hand, when the lever 23 is turning in the opposite, or in a counterclockwise direction, the spring 36 will allow the free end of the ratchet dog 34 to yield outwardly, thereby permitting its free end to ride over the teeth of the ratchet wheel 17 so that the lever can swing relatively to the ratchet wheel and to the well rod 15.

The pumping jack 10 is operated in a conventional manner by means of a pulling force exerted on a rod 37, which forms a part thereof, in a direction as indicated by the arrow 38 (Figure 1) for rocking jack frame 11 to swing the pitman 14 and the walking beam 13 upwardly to thereby move the well rod upwardly. The weight of the well rod and the parts attached thereto will cause the well rod to slide downwardly and to swing the walking beam 13 and the other pivoted parts in the opposite direction and to move the connecting rod 37 in the opposite direction, to the direction indicated by the arrow 38. The bar 20 projects from the well rod 15 in a direction toward the right, looking toward the well rod and the pumping jack 10 from the lefthand end of Figure 1. Consequently, on the down or gravity stroke of the well rod 15 as the pumping jack frame 11 is swinging toward the well rod and as the connecting rod 29 is being moved toward a horizontal position, it will be readily obvious that a push will be exerted on connecting rod 29 by the frame 11 for turning the lever 23 in a clockwise direction, as seen in Figure 2, to partially revolve the ratchet wheel 17 and the well rod 15. As previously pointed out, this will require no power other than that exerted by the downward gravity pull of the well rod. On the upstroke of the well rod, lever 23 will be turned in a counterclockwise direction back to its original position, by the pull exerted thereon by rod 29, and in so moving the free end of the ratchet dog 34 will ride over the teeth of the ratchet wheel 17, as previously explained. It will thus be obvious that the well rod 15 will be partially revolved on each stroke thereof to likewise revolve parts connected thereto

relatively to the working barrel of the pump. The extent to which the well rod 15 will be turned with each stroke thereof will constitute only a part of a revolution and can obviously be varied by adjusting the yoke 28, relatively to the lever 23, by positioning the fastening 27 in different openings 26.

Counterweight 25 is provided to counterbalance the weight of the connecting rod 29, yoke 28 and dog 34, and may be adjusted longitudinally of the bar 19 for correctly balancing the lever 23.

Various modifications and changes are contemplated and may obviously be resorted to, as only a preferred embodiment of the invention has been disclosed.

I claim as my invention:

1. In combination with a pumping jack and a well rod connected thereto and actuated thereby, a ratchet wheel adapted to be keyed to the well rod above the walking beam of the pumping jack, a lever rotatably connected to the well rod, a connecting rod connected at one end to an end of said lever and connected at its opposite end to the rocking frame of the pumping jack, a ratchet dog pivotally connected at one of its ends to said lever, between the well rod and the connecting rod, and extending from the side of said lever, opposite the side from which the connecting rod projects, the free end of said dog being disposed to engage the teeth of the ratchet wheel, a contractile coil spring connected at one end to the intermediate portion of said dog and anchored at its opposite end to the lever for yieldably positioning the free end of the dog, relatively to the lever so that the dog will ride over the teeth of the ratchet wheel when the lever is turned in one direction, relatively to the well rod and will engage with the teeth of the ratchet wheel for turning the ratchet wheel and well rod, when the lever is swung in the opposite direction, said lever being arranged to engage and turn the ratchet wheel and well rod on the down or gravity stroke of the well rod.

2. An apparatus as in claim 1, said lever including two bars, one of the bars having an opening intermediate of its ends for turnably engaging the well rod, above the ratchet wheel, the other bar having an opening adjacent one end thereof from turnably engaging the well rod, beneath the ratchet wheel, said bars having complementary overlapping ends connected by spaced nut and bolt fastenings, said dog being mounted on one of said fastenings and said spring being anchored to the other fastening, and said connecting rod being connected to the opposite end of the last mentioned bar.

JAMES O. WILSON.
